(57) **CLAIM**

The ornamental design for a delivery robot as shown and described.

DESCRIPTION

The patent or application file contains at least one drawing executed in color. Copies of this patent or patent application publication with color drawing(s) will be provided by the Office upon request and payment of the necessary fee.

1. Delivery robot

1.1 : Front perspective view

1.2 : Back perspective view

1.3 : Front

1.4 : Back

1.5 : Left

1.6 : Right

1.7 : Top

1.8 : Bottom

1.9 : Reference view

1.10 : Reference view

The characteristic features of the design lie in the combination of the shape and pattern; the broken lines shown in reproductions 1.1 to 1.8 depict portions of the delivery robot and form no part of the claimed design; reproduction 1.9 is a partially enlarged view of reproduction 1.1 showing a state of use and reproduction 1.10 shows a state of the door opened in use; the other broken lines and colors shown in reproductions 1.9 and 1.10 illustrate environmental structure and form no part of the claimed design; the shading lines are used to show the surface of the claimed design and do not represent its surface ornamentation.
